Primary Examiner — Paula Allen Greene*(74) Attorney, Agent, or Firm* — Workman Nydegger(57) **CLAIM**

The ornamental design for a headband for headphones as shown and described.

DESCRIPTION

FIG. 1 is a perspective view of a headband for headphones showing the new design;

FIG. 2 is second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The features shown in evenly broken lines do not form part of the claimed design.

1 Claim, 7 Drawing Sheets# US D1,098,070 S
